AIR PREHEATING APPARATUS

Gerhard Niemitz, New York, N. Y., assignor, by
mesne assignments, to Kennedy-Van Saun
Mfg. & Eng. Corporation, New York, N. Y., a
corporation of Delaware

Application May 26, 1938, Serial No. 210,149

9 Claims. (Cl. 257—2)

This invention relates to air heating means wherein the air is heated by the transfer of the heat of a heated fluid such as the waste gases or products of combustion of a boiler furnace or kiln, and the preheated air mixed with and constituting a part of a fluent fuel, such as pulverized coal, or delivered to the pulverizing chamber of a coal pulverizer to absorb the moisture content and dry the coal as it is pulverized and mixed with the pulverized coal to serve as the conveying vehicle therefor and comprise a combustible fuel, or the preheated air delivered to the place of combustion of fuel to constitute a secondary air supply to be mixed with the fuel during the combustion thereof.

Air preheaters of this character comprise a casing arranged with a chamber at one end having an inlet for the passage of the waste gases or products of combustion, a chamber at the opposite end having an outlet for the gases adapted to be connected to a stack, and a chamber intermediate said inlet and outlet chambers having ducts in the form of tubes extended therethrough and fixed at the opposite ends in openings in the separating walls for the passage of the waste gases or products of combustion, the intermediate chamber also having an air inlet to one end and a side thereof, and an outlet from the opposite end and side thereof to cause the air to pass through said chamber in a direction opposite to the flow of the gases through the ducts and traverse said ducts in the passage of the air through the chamber to transfer the heat of the gases to the air.

In the use of the apparatus in connection with a coal fired boiler furnace the intermediate heat transfer chamber of the apparatus is of a capacity and provided with a number of ducts so that the apparatus will operate to efficiently heat a volume of air to a temperature sufficiently high to absorb the moisture content and dry the coal as it is pulverized when the boiler furnace is operating under high load, however, when the boiler furnace is operated under a low load it will not operate to heat the air to the desired and necessary temperature for the efficient operation of the pulverizer and furnace.

It is the object of the invention to provide an improved air heating apparatus of this character to overcome the above disadvantages and operate to heat the air to a desired temperature when the boiler furnace is operating under both low and high loads, and to provide apparatus for this purpose that is simple in construction and efficient in use.

It is a further object of this invention to provide air heating apparatus of this character including a casing arranged with a chamber at one end having an inlet for the waste gases of combustion, a chamber at the opposite end having an outlet for said gases and a chamber intermediate said end chambers arranged with a series of passes open to each other at opposite sides of the casing and said casing having an inlet and an outlet for the air to be heated in communication with said passes, and each pass arranged with a series of ducts for the passage of the gases with one series in communication with the gas inlet, and the provision of means to cause the gas to pass through one series of ducts or all of the series of ducts from the gas inlet to the gas outlet, and means to cause the air to pass through and traverse the ducts in one of the passes, or pass successively through and traverse the ducts in all of the passes from the air inlet to the air outlet.

It is a further object of the invention to provide an air heating apparatus of this character having multiple passes for the gases and air, and means to separate ash and other foreign substances from the gases, and means to induce a flow of the gases through the apparatus and the connecting of said means and the separator in the connection of the outlet for the gases with a stack.

Other objects and advantages of the invention will hereinafter appear.

In the drawings accompanying and forming a part of this application,

Figure 1 is a longitudinal sectional view of apparatus for heating air by waste gases of combustion and showing the same connected to a stack with a fan and separator interposed in the connections thereof with the stack and showing an embodiment of the invention, the section of the air heating means being taken substantially on the line 1—1 of Figure 2 looking in the direction of the arrows.

Figure 2 is a longitudinal sectional view taken substantially centrally through the air heating apparatus of Figure 1 and showing the inlet for the waste gases of combustion connected in communication with the outlet for the exit gases of a boiler furnace.

Figure 3 is a cross sectional view taken substantially on the line 3—3 of Figure 2 looking in the direction of the arrows, and

Figure 4 is a view similar to Figure 3 on a reduced scale and showing another position of ad-

justment of means for directing the flow of air through the apparatus.

In the embodiment of the apparatus illustrated in the drawings for carrying out the invention there is provided a substantially rectangular casing supported in vertically disposed position and shown as arranged at the rear of a boiler furnace a part of which is shown in a general way at B in Figure 2. The casing comprises side walls 5, 6, end walls 7, 8, a top closure wall 9 and a bottom wall in the form of a double hopper 10, 10' with the side wall 5 terminating in spaced relation to one wall of the hopper 10 providing an opening to the bottom of the casing, the opening consisting in effect a continuation of the outlet pass for the exit of the waste gases or products of combustion from the boiler furnace, said gases passing into the hopper bottom in the direction indicated by the arrows a. A partition 11 extending transversely of the casing adjacent to but spaced from the hopper bottom provides a chamber between said partition and the hopper bottom separated by a vertical wall 12 into two portions C and C' with the inlet for the hot gases of combustion to the portion C. A partition 13 extending transversely of the casing adjacent to and spaced from the top closure 9 provides a chamber C2 for the gases having an outlet 14 at one end thereof. The partitions 11, 13 arrange the casing with a chamber intermediate the chambers C, C' and C2, said chamber being provided with a series of passes for the air, shown as three in number, by partitions 15 fixed in and extending longitudinally between the transverse partitions 11, 13, the partitions 15 being spaced laterally from the sides 5, 6 of the casing and each other, and providing the chamber with the three passes P, P' and P2. The partitions are of the same width and of a width less than the width of the casing between the walls 7, 8 and spaced from said walls thereby providing passes P3, P4 at opposite sides of the casing open to and connecting the passes P, P' and P2 in communication with each other through said passes P3 and P4.

The pass P4 has an inlet at the top and a side of the casing for the air to be heated and the air pass P3 has an outlet 17 for the heated air arranged at the bottom and side of the casing opposite the air inlet 16. The passes P, P' and P2 are of successively less width, the pass P being of least width and the pass P2 of greatest width.

A plurality of series or sections of ducts in the form of tubes are provided, and shown as three in number; one section T extends longitudinally of the air pass P, another section T' extends longitudinally of the air pass P' and another section T2 extends longitudinally of the air pass P, the tubes at one end being secured in openings in the partition 13 and opening to the outlet chamber C2, and secured at the opposite ends in openings in the partition 11 and opening to the portions C, C' of the hopper bottom at the opposite end of the casing with the section of tubes T in communication with the gas inlet to the portion C and the other sections T' and T2 in communication with the portion C' and connected in communication with each other at said end through the portion C'.

By the arrangement of the air inlet 16 and the air outlet 17 the air to be heated is caused to flow through the passes and traverse the ducts or tubes in a direction reverse to the flow of the

waste gases of combustion through the ducts or tubes.

The air to be heated is caused to pass through one of the air passes between partitions 15 and traverse the tubes in said pass, such as the air pass P2, should the load on the boiler furnace be low and thus assure the heating of the air to a relatively high temperature, the air flowing from the inlet to the outlet in the direction indicated by the arrows b shown in Figure 3. Should the boiler furnace be under a high load the air is caused to flow through all of the passes between the partitions 15, the air flowing as indicated by the arrows c from the inlet 16 through the passes P, P3 and P' and from the latter pass 15 through the passes P4 and P3 to the outlet 17. For this purpose adjustable partitions 18, 19 are arranged in the passes P3 and P4 to extend longitudinally and transversely thereof, the one partition 18 being pivotally supported at a longitudinal edge portion at the end of the partition between the passes P' and P2, as at 20, and the other partition 19 pivotally supported at a longitudinal edge portion at the end of the partition between the passes P and P'. In the position shown in full lines in Figure 3 the air passes successively through the passes P, P3 and P' and from the latter through the passes P4, P2 to the outlet 17. To cause the air flowing through the inlet 16 to only traverse the ducts in air pass P2, the adjustable partition 19 is adjusted to the dot and dash line position 19' shutting off the air pass P from the inlet and the adjustable partition 18 shutting off the outlet from the air passes P and P' from the air pass P3. In some instances while the boiler furnace is operating under high load it may be desirable not to heat the air to a very high temperature. In this case the air may be caused to traverse only the ducts or tubes in the air pass P arranged with the least number of ducts. For this purpose the partitions 18, 19 are adjusted to the positions shown in Figure 4, the partition 19 shutting off the inlet from the pass P4 and thereby cause the air to pass from the inlet through and traverse the ducts in the air pass P and flow from the pass P through the pass P3 directly to the outlet.

The adjustable partitions 18, 19 are adapted to be automatically actuated and the actuation thereof controlled by the temperature of the waste gases of combustion exiting from the air preheater to a stack S. For this purpose the pivot support of the partitions 18, 19 are connected to actuating means, as shown in a conventional manner at 22 in Figure 1 connected to the pivot support 21 of the partition 19, and said means actuated and the actuation thereof controlled by a temperature responsive element attached to the stack and said actuating means, as shown in a conventional manner at 23 in Figure 1.

To cause the waste gases of combustion to pass or flow only through the section or series of tubes T in the air pass P2 when the boiler furnace is operating under low load, and cause said gases to pass through all of the duct sections T, T' and T2 when the boiler furnace is operated under high load, an adjustable partition 24 is arranged in the gas outlet chamber C2 to extend transversely thereof, the partition being connected to a pivot support 25 extending longitudinally thereof and parallelly of and at the end of the partition between the air passes P, P'. To cause the gases to pass through all of

the sections of the tubes T, T' and T² when the boiler furnace is operating under high load the partition 24 is adjusted to the position shown in full lines in Figure 2 to extend transversely of the chamber C² when the gases will flow in the direction of the arrows a through the tubes T, from said tubes the gases flow reversely through the section of tubes T', and from said latter tubes into the portion C' of the hopper bottom and then reversely through the tubes T² to the outlet 14 and thence to the stack S. When the boiler furnace is operating under low load the partition 24 is adjusted to the position shown in dotted lines 24' extending transversely of the ends of the section of the tubes T' opening to the chamber C², the gases flowing from the tubes T through the chamber C² to the outlet 14. The partition 24 is adapted to be actuated automatically and the actuation thereof controlled by the temperatures of the gases of combustion exiting through the stack S, and actuated in synchronism with the actuation of the adjustable partition 19, for which purpose the pivot support of the partition 24 is connected to actuating means, such as 22 shown in connection with the partition 19, and the actuation thereof controlled by a temperature responsive element, such as 33, attached to the stack S and the actuating means 22.

30 The outlet for the gases may have a natural draft connection with the stack S through a conduit 26 or the flow of the gases through the tubes or ducts of the air preheater to the stack may be induced as by a fan F the outlet of which is connected to a stack and the inlet connected to the conduit 26 to connect the inlet of the fan with the outlet 14 for the gases from the chamber C² of the air preheater. The conduit 26 has a regulatable connection with the stack, shown 40 as a damper 27, which is adjusted to shut off the conduit 26 from the stack when the flow of the gases is induced by the fan F.

To separate foreign substances from the gases, such as soot, fly ash and the like before the gases exit to the stack S a separator is interposed in the connection of the fan with the gas outlet 14, and shown as of the centrifugal type consisting of a body 28 having a hopper bottom and a conduit 29 extended centrally into the top of the body 50 to substantially midway the top and bottom and in effect constituting a continuation of the conduit 26. Inlet means 30 to the body is connected to the outlet 14 of the air preheater for the exit gases, said inlet means being arranged to cause 55 the gases admitted into the body of the separator to swirl about the outlet conduit 29 thereby causing particles of foreign substances to separate from the gases and drop to the hopper bottom of the separator bottom, the gases passing upwardly to the conduit 29 either through the fan as indicated by the arrows, or through the conduit 26 to the stack S.

It will be obvious that various modifications may be made in the construction and arrangement of the parts without departing from the scope of the invention and that portions of the invention may be used without others and come within the scope of the invention.

Having described my invention, I claim:

70 1. Means for heating air by waste gases of combustion, comprising a rectangular casing having an inlet for the gases at the bottom and a side thereof and an outlet for the gases at the top in the opposite side thereof and an inlet at the top and an end thereof and an outlet at the bot-

tom and opposite end for the air to be heated, a plurality of sections of ducts extending longitudinally of the casing, one section being in communication with the gas inlet, adjustable means operative in one position of adjustment to cause the gases to pass through the section of the ducts in communication with the gas inlet directly to the gas outlet and in another position of adjustment cause the gases to pass in series through all of the duct sections to the gas outlet, and adjustable means operative in one position of adjustment to cause the air to traverse transversely and lengthwise of one section of ducts from the air inlet to the air outlet and in another position of adjustment cause the air to traverse transversely and longitudinally in series all of the sections of ducts from the air inlet to the air outlet. 15

2. In means for heating air by waste gases of combustion, a rectangular casing having transverse partitions arranging said casing with a chamber at the top and bottom of the casing and a chamber intermediate said chambers, said bottom chamber being separated into a pair of compartments and one compartment having an inlet for the gases of combustion at one side of the casing, and the top chamber having an outlet for said gases at the opposite side of the casing, conducting tubes for the passage of gases extending longitudinally of the casing through the intermediate chamber and connected at one end 30 in communication with the top chamber, a series of said tubes being connected at the opposite ends in communication with the compartment in the bottom chamber having the inlet for the gases and the remainder of the tubes in communication with the other compartment in said bottom chamber, and adjustable means in the chamber having the outlet for the gases operative in one position of adjustment to cause the gases to pass through the tubes in communication with the gas 40 inlet chamber directly to the gas outlet, and in another position of adjustment cause the gases passing from said tubes to flow reversely through an adjacent series of the tubes into the other compartment in the chamber, and thence from 45 said compartment flow reversely through another series of the tubes to the gas outlet, and the intermediate chamber having an air inlet to the top thereof at one end of the casing and an air outlet from the bottom of said chamber 50 through the opposite end of the casing and cause the air to be heated to traverse transversely and longitudinally of the tubes from the air inlet to the air outlet.

3. In means for heating air by hot waste gases 55 of combustion, a rectangular casing, transverse plates arranging the casing with a chamber at the top and bottom of the casing and a chamber intermediate said chambers extending longitudinally for the greater portion of the casing and the bottom chamber separated into two compartments, one compartment having an inlet at a side of the casing for the gases and the chamber at the top having an outlet at the opposite side of the casing for said gases, fixed partitions 60 of less width than the width of and extending longitudinally of the casing and spaced laterally from the side walls of the casing and each other arranging the intermediate chamber with passes at the opposite ends thereof and a series 65 of three passes at right angles to and open for the entire length at the opposite sides to said end passes, tubes extending longitudinally through each of the passes between said partitions secured at the ends in openings in the 70 75

- transverse partitions connecting all of said tubes at one end in communication with the top chamber, and connecting the section of tubes in one pass in communication with the bottom compartment having the inlet for the gases and connecting said ends of the tubes in the other passes in communication with the other compartment in said bottom chamber, an adjustable partition in the chamber at the top of the casing adapted 5 to one position of adjustment to cause the gases flowing through the section of tubes in communication with the inlet for the gases to flow from said tubes directly to the outlet of said top chamber, and in another position of adjustment 10 cause the gases to flow reversely in series through the sections of tubes in the successive passes to the gas outlet from the top chamber and said casing having an inlet for the air to be heated to the top of an end pass in the intermediate 15 chamber and an outlet for the heated air from the bottom of the other end pass in the intermediate chamber to cause the air to traverse transversely and lengthwise of the tubes in the passage of the air through the intermediate 20 chamber from the air inlet to the air outlet. 25
4. In means for heating air by waste products of combustion as claimed in claim 3, adjustable partitions in the end passes of the intermediate chamber in the casing adapted to be 30 adjusted to cause the air to traverse the tubes in either one of two of the passes between the partitions in the flow of the air from the inlet to the outlet, or to cause the air to flow in series through all of said passes and traverse 35 the tubes therein to the outlet, and thermostatically operative means actuated by the temperature of the gases existing from the outlet for the gases to adjust the partition.
5. In means for heating air by hot waste gases 40 of combustion as claimed in claim 3, adjustable partitions in the end passes of the intermediate chamber in the casing adapted to be adjusted to cause the air to flow from the air inlet through and traverse the tubes in one pass between the partitions to the outlet and to cause the air to flow in series through and traverse the tubes in all of the passes between the partitions to the outlet. 45
6. In means for heating air by waste gases of 50 combustion as claimed in claim 3, adjustable partitions in the end passes in the intermediate chamber operative in one position of adjustment to cause the air to traverse the tubes in either one of the end passes in the flow of the air from the inlet to the outlet of said chamber, and in another position of adjustment of said partitions cause the air to flow from the inlet in series through all of the passes and traverse the tubes 55 therein to the outlet.
- 60 7. In means for heating air by waste gases of combustion as claimed in claim 2, wherein the means in the chamber having the outlet for the gases to cause the gases to pass through one or all of the sections of the tubes in series comprises an adjustable partition in said chamber, and thermostatically operated means actuated by the temperature of the gases exiting from the outlet of said chamber connected to and operative to adjust the partition.
- 65 8. In apparatus for heating air by waste gases of combustion, a rectangular casing having a chamber at the bottom and arranged with a pair of compartments and one compartment having an inlet for the gases of combustion, a chamber at the top end of the casing having an outlet for 70 said gases, and an intermediate chamber having an air inlet to one side and upper portion of said chamber and an outlet from the opposite side and bottom portion of said chamber, tubes extending through the intermediate chamber connected in communication with the top and bottom chambers of the casing with a section of said tubes in communication with the compartment of the lower chamber having the inlet for the waste gases of combustion, adjustable 10 means in the gas outlet chamber operative in one position to cause the gases flowing from the section of the tubes in communication with the gas inlet to flow from the upper chamber to the outlet thereof and in another position cause the 15 gases to flow in series through successive sections of the tubes to the gas outlet, means to arrange the intermediate chamber with multiple passes, and adjustable means operative in one position to cause the air to pass from the air inlet through 20 one pass and transversely and longitudinally traverse the tubes therein to the outlet and in another position cause the air to pass through another of the passes and transversely and longitudinally traverse the tubes therein to the 25 outlet, and in another position thereof cause the air to pass in series through and transversely and longitudinally traverse the tubes in all of the passes to the outlet.
9. In apparatus for heating air by waste gases 30 of combustion, a casing arranged with a chamber at the bottom having an inlet for the hot gases of combustion, a chamber at the top having an outlet for said gases and an intermediate chamber, fixed partitions extending longitudinally of and spaced laterally from each other in the intermediate chamber and of less width than the width of the casing arranging said chamber with a series of three passes between said partitions and passes at the opposite ends of said passes, one of said passes constituting an air inlet pass having an inlet opening to the upper portion thereof at a side of the casing and the other pass constituting an air outlet pass having an outlet opening from the lower portion thereof at the side of the casing opposite the side with the air inlet opening, a partition in the air inlet pass pivotally mounted at a longitudinal edge in line with the partition separating an end pass from the intermediate pass of the series of passes, said partition being of a length and width equal to the length and width of said inlet pass and adapted in one position to extend transversely of the inlet pass and cause the air to pass from the air inlet through said end pass of the series of passes to the outlet pass, and in another position of adjustment shut off said end pass of the series of passes from the inlet and cause the air to pass through the other end pass of the series of passes to the outlet pass, 40 and a partition in the air outlet pass pivotally mounted at a longitudinal edge in line with the partition separating the other end pass from the intermediate pass of the series of passes, said partition being of a length and width equal to the length and width of the outlet pass and adapted in one position thereof to extend transversely of the outlet pass and cause the air flowing from the one end pass of the series of passes into the outlet pass to flow reversely through the 45 intermediate pass of the series of passes into the inlet pass and thence through the other end pass of the series of passes to the outlet pass, and in another position thereof permit the air flowing from the one end pass into the outlet pass 50
